SKY WRITING APPARATUS
Anthony Stinis, 85-43 Chevy Chase St.,
Jamaica Estates, N.Y.
Filed Aug. 18, 1961, Ser. No. 132,339
2 Claims. (Cl. 40—213)

This invention relates to an apparatus and method of sky writing wherein a number of planes flying in formation co-operate in producing the writing.

It is known to use a plurality of planes for forming sky writing wherein each plane is assigned a certain part of a letter. Such prior systems may use records, similar to player piano records and consisting of a blank provided with slots shaped in the pattern it is desired, for the particular plane to write. The slotted blank is used to make and break an electric connection thereby generating signals of a desired duration and placement. These signals are generated in a particular plane and are then transmitted to the other planes over separate communication channels.

In prior art sky writing systems, it is also conventional to transmit identical synchronizing signals which serve to synchronize the various letter or character patterns for the different planes. In such systems, the patterns are determined by a selector system in each plane; the selection being accomplished by multi-contact switches which normally represent expensive and complicated equipment.

An object of the present invention is to simplify and render more economical present systems of sky writing.

A further object of the invention is to control the sky writing by a formation of planes from perforated tapes on a lead plane.

Another object of the invention is to control sky writing from the auxiliary controlled planes by transmitters of radio or audio frequency tones, selectively radiated from the control plane by perforated message tapes.

A feature of the invention is a moving message tape located in the control plane, wherein perforated characters or letters are sensed by photoelectric cells to control the transmission of separate radio frequencies from the control plane to the other planes, whereby the planes will emit smoke patterns of said characters.

In accordance with the present invention, a number of planes fly in parallel and with substantially equal speed following a straight line so that they are at all times aligned at right angles, or any type of angle desired, to the direction of flight, each plane being equipped with smoke emitting apparatus.

The emission of smoke puffs is determined by a plurality of transmitted discrete frequencies situated in the radio or audio band, which control an equal number of planes from a central or lead plane. On the control plane, the messages inscribed on perforated tape are sensed to activate a group of photoelectric cells in accordance with a dot pattern representing the characters of the message. Transmitters on the lead plane energized selectively and photo-electrically radiate a series of discrete frequencies under the control of the photoelectric cells. When these frequencies are selectively received by a controlled plane, it responds by emitting smoke puffs in accordance with the dot pattern of the characters in a message.

More than one message may be handled by two perforated tapes, which utilize switching from one to the other, controlled by reset perforations located on the tapes at the end of a message. The reset perforations are photo-electrically scanned to switch between tapes and messages.

Other advantages of the present invention will become apparent when considered in connection with the following specification and drawing, wherein:

FIGURE 1 is a perspective view of a message tape for sky writing in accordance with the present invention.

2

FIGURE 1a is a block schematic diagram of a perforated tape and the radio transmitting apparatus located in the control plane.

FIGURE 2 is a circuit schematic corresponding to the block diagram of FIGURE 1a.

Referring to FIGURE 1, one manner in which a script is formed is illustrated. Each letter or character is composed of a pattern of apertured dots on a perforated tape A or B on which the letters E, V and B are typically represented. The numbers 1 to 5 in the first vertical column of the letter E correspond to the planes 1 to 5 from which the smoke puffs are to be emitted. Plane 1 represents the lead plane on which the control apparatus consisting of perforated tapes A and B and radio transmitters (f5, f2, f3, f4) or the like are located. Planes 2 to 5 represent the controlled planes on which the single or multi-tone receivers for picking up the discrete (f5, f2, f3, f4) frequencies are situated for controlling the corresponding smoke valves, respectively.

It is apparent then that any character or dot pattern (as the letter E) appearing on the perforated tape will cause the formation of airplanes to emit puffs of smoke representing the vertical columns of apertures, which form an E in FIGURE 1. For example, to form the first vertical column of dots contained in the letter E (see FIGURE 1), the control plane 1 will emit a puff of smoke directly when dot 1 is scanned photo-electrically. Simultaneously, control plane 1 radiates four separate frequencies, f2, f3, f4, and f5 from its four radio transmitters respectively located thereon. The radiated frequencies, f2, f3, f4, and f5 are picked up by corresponding radio receivers in planes 2, 3, 4 and 5 (not shown). Upon receiving its characteristic frequency, each controlled plane emits a puff of smoke from its smoke valve thereby contributing to the formation of the pattern of five dots, as the first vertical column in the sky writing of the letter E.

Referring to FIGURE 1a, a perforated tape 1 is moved by means of a motor 2 past a block of light 3 registering with a corresponding bank of photo cells 3 aligned therewith. The taped message, consisting of perforated characters, is conveyed between the lights 3 and photo cells 4, will operate a corresponding array of relays 1 to 5 selectively. The pattern of operated relays 1-5 corresponds selectively to the vertical columns of dot patterns previously illustrated in connection with FIGURE 1 and the letter E, for example.

Thus, the first vertical pattern of dots from which the character E is formed, produces a selective pattern of photo cells 1 to 5 activated, and the corresponding array of relays 1 to 5 energized. Similarly, the second column of dots characterizing the letter E contains only dots 1, 2 and 5. Consequently, when the perforated tape A passes in front of the photo cells, only cells 1, 2 and 5 and corresponding relays 1, 2 and 5 operate. The control plane 1 directly emits a puff of smoke from its exhaust smoke valve 1 and simultaneously transmits two radio frequencies, namely f2 and f5, which are picked up by planes 2 and 5 to control the emission of puffs of smoke from their exhausts, respectively.

It should be noted that the other two transmitter frequencies f3 and f4 are not radiated for the second column of dots, so that planes 3 and 4 do not respond by emitting puffs of smoke from their exhausts respectively.

In this manner, the second column of dots in forming the letter E is written and the planes continue to fly in formation scanning the successive columns of dots which constitute the complete characters and message.

By way of summary, the sky writing of letter E in accordance with the present invention involves a pattern of radiated radio or audio frequencies sent by the control plane 1 to the other planes in accordance with the following scheme:

3
Letter E

Planes:	Transmitted Frequencies
Plane 2	f_2
Plane 3	f_3
Control Plane 1	
Plane 4	f_4
Plane 5	f_5

The pattern of signalled frequencies for the letter E and the resultant puffs of smoke from the various planes are represented in the above table, where the vertical dots in the formation of the letter E represent smoke puffs from each plane's exhaust, respectively.

The power for the sky writing system shown in FIGURE 1a is applied from the +12 volt source 20 when the "on" switch 22 is thrown to operate the A latch relay 24. The reversible D.C. motor which moves the perforated tape or belt 3, is simultaneously energized by the same +12 volt source. The A tape 3 bearing a perforated message thereon is displaced by the D.C. motor 2 between a block of lights 4 energized by the relay 24 and a corresponding block of photo cells 5 aligned with the lights and registering therewith.

The block of five photo cells 5 corresponds in number to that of the plane formation. This block of photo cells is selectively operated by the perforation patterns which make up a character on the endless tape A. More particularly, each vertical column of perforations illustrated in FIGURE 1 for the letter E is sensed as a unit by the photo cell block 5. When the photo cells are energized in accordance with the perforation pattern of FIGURE 1, they energize selectively a group of five photo cell relays 31 to 35. When the photo cell relay 1 operates, it causes the smoke valve 1 of the lead or control plane to emit a puff of smoke directly from its exhaust. The controlled planes 2 to 5 only puff smoke upon the reception of their own characteristic tone frequency as transmitted thereto from the control plane 1. When cell relays 2 to 5 are operated by the perforated patterns on the tape A, radio transmitters 2, 3, 4 and 5 selectively radiate single tone frequencies f_2 , f_3 , f_4 and f_5 , from the control plane, to control the action of the exhausts in the controlled planes.

The end of a message on the tape A is signalled by the presence of a reset perforation placed at the end of the message as illustrated in FIGURE 1. The reset perforation is instrumental in operating a sixth photo cell 6 from reset light 7, whereupon reset A relay 36 operates. As a consequence of the reset operation, B latch relay 25 operates together with cross-over switch 38 and on switch 23 to initiate the movement of perforated message tape B by the D.C. motor 2 and power switch 23 for sending a second message. At this point, tape A is stopped by off switch 39 having been operated by the reset dot. The second tape B sends its message translated into puffs of smoke in the control and controlled planes in a manner corresponding to that previously described for tape A. In the operation of tape B, a similar bank of photo cells 5B and lights 4B are selectively operated by the tape to energize photo cell relays 1 to 5 in the manner previously described for tape A. At the end of the message sent by tape B, a reset perforation thereon correspondingly controls the switching reset B relay 27 to stop tape B message.

The lead pilot then can push start switch on A or B for another start on whatever message is desired. These tapes are accessible to lead pilot and can be changed during flight in a matter of minutes for a different advertiser.

It is significant that the tapes A and B can be changed by the lead pilot in a matter of only two minutes while in flight so that the planes can write different characters without landing. This is virtually impossible to do with other known methods of sky-writing. Previously all planes had to land and all stepping switches changed in all 5 planes by the 5 pilots in order to write a different

message. This took approximately one hour or more, on the ground, plus time taken in landing, taking off and climbing back up to 10,000 feet, which could take another hour or more all told.

In the sky writing circuit shown in FIGURE 2, which corresponds to the block schematic of FIGURE 1a, transmitters 2, 3, 4 and 5 may be either radio frequency or audio frequency tone transmitters, and are present only on the control plane 1. The tone receivers individual to the controlled planes 2-5 are not shown, but they utilize conventional radio or audio apparatus, apparatus capable of picking up their own individual frequency or tone. The group of transmitters 2-5 can be selectively operated from either tape A or tape B through the common group of photo cell relays 1-5 actuated by the vertical patterns of perforations, forming the characters in the manner previously illustrated in FIGURE 1.

Also, conventional photoelectric cells 5 and photo cell relays are suited to the system described.

20 The 12 volt D.C. motor 2 may be operated in a forward direction or reversed by means of switch 41 and its speed may be controlled by potentiometer 42 and drive gears 43.

25 The smoke valves which control oil sources connected to the exhaust pipe of the planes are conventional, and well-known in the art of sky writing.

30 It should be appreciated that single or multiple tones or double tones in communications bands, for example, between the audio and radio range or in the microwave range may be utilized for the disclosed system without departing from the spirit of the invention. It should also be appreciated that other scanning and sensing methods corresponding to applicant's optical and photoelectric devices may be utilized in the practice of the invention without departing from the spirit thereof.

35 Likewise, the single radiated frequencies f_1 , f_2 , f_3 and f_4 disclosed may be combined with tones; also carrier frequencies may be transmitted, modulated by audio tones without thereby departing from the spirit of the invention.

40 Whereas a particular embodiment of the invention has been described, it should not be construed as limiting, and it is desired therefore that the invention be interpreted as broadly as the scope of the appended claims.

45 What I claim and desire to secure by Letters Patent is as follows:

1. In apparatus for selectively controlling the emission of sky writing smoke from the exhaust pipes of a plurality of airplanes flying in formation, one of said airplanes being the control airplane and the remaining being controlled airplanes, the combination comprising a plurality of perforated message tapes, mounted on rollers, drive means operatively connected to said rollers to drive said tapes, each said tape having a plurality of rows of perforations formed therein, one row for each controlled airplane in such formation (alternately energizable), scanning means operatively connected to said tapes, there being one group of scanning means for each said row of perforations, and a plurality of radio transmitters, each transmitting on a different frequency, one for each said controlled airplane, said transmitters being connected to said scanning means and adapted to transmit signals corresponding to each said row of perforations as scanned by said scanning means, said perforated message tape, scanning means and radio transmitters being located in said control airplane, and a plurality of radio receivers tuned to the frequencies of said transmitters and adapted to receive signals from said transmitters, there being one such receiver in each said controlled airplane, and smoke control valve means controlling the emission of sky writing smoke in each of said controlled airplanes, each of said receivers being operatively connected to the smoke control valve means in the same controlled airplane to control the emission of smoke therefrom in accordance with the signals received from its associated transmitter.

2. In apparatus in accordance with claim 1, wherein the

scanning means includes a plurality of photocells which are activated through the perforations on said perforated message tape, said photocells being situated on one side of the perforated message tape and a light source being provided on the opposite side thereof to transmit light through said perforations to said photocells, said photocells being in circuit with said transmitters, there being one such photocell for each row of perforations and hence for each transmitter.
